DESIGN FOR A ROTARY MACHINE TOOL

Umberto Anesi, Chicago, Ill.

Application August 4, 1940, Serial No. 94,341

Term of patent 7 years

To all whom it may concern:

Be it known that I, Umberto Anesi, a citizen of the United States, residing at Chicago, in the county of Cook and State of Illinois, have invented a new, original, and ornamental Design for a Rotary Machine Tool, of which the following is a specification, reference being had to the accompanying drawing, forming a part thereof.

Figure 1 is a perspective view of a rotary machine tool showing my design.

Fig. 2 is a top plan view of the machine tool.

The side and end opposite to those shown are substantially similar.

I claim:

The ornamental design for a rotary machine tool, substantially as shown and described.

UMBERTO ANESI.
